ANDREW WYLEY, OF BIRMINGHAM, ENGLAND.

Letters Patent No. 84 459, dated November 24, 1868; patented in England, March 25, 1867.

IMPROVEMENT IN BREECH-LOADING FIRE-ARMS.

The Schedule referred to in these Letters Patent and making part of the same.

To all whom it may concern:

Be it known that I, ANDREW WYLEY, of Birmingham, England, have invented certain new and useful Improvements in Breech-Loading Fire-Arms; and I do hereby declare that the following is a full, clear, and exact description thereof, reference being had to the annexed drawing, making a part of this specification.

My invention consists in the construction and employment, for closing the breech in fire-arms, of a compound bolt, consisting of a more or less cylindrical plug or plunger, having a reciprocating motion in the line of the barrel, and a bolt, of T-shape, transverse to the same, by which it is locked to the breech-case or rearward continuation of the barrel.

The T-bolt, in the unlocked state, serves as a handle for working the plunger, which, by a forward motion, pushes the cartridge into the barrel.

By the reverse motion, the arm is cocked, and the cartridge extracted by means of a suitable extractor, attached to or forming part of the plunger, except when the cartridge is of such a nature as to be partially consumed and blown forward.

Figure 1 is a longitudinal vertical section of the above compound bolt, as applied to a fire-arm, using a long central fire-cartridge, and

Figure 4, an elevation of same, when unlocked and drawn back.

Figure 7 is a perspective view of such fire-arm.

Figure 5 is a cross-section behind the transverse or T-bolt.

Figure 6 is the same, but with the T-bolt modified.

Figure 10 shows a form of striking-pin used with the last.

Figures 2 and 3 are perspective views of the plunger-head and of the extractor.

Figure 1^a is a side elevation of a compound bolt, adapted to a flange-fire cartridge.

Figure 8 is a sectional elevation of a fire-arm, modified from the above, in which the hammer and main-spring are replaced by a spiral spring and striker-disk O, while the fore end of the bolt is formed to suit a partially-combustible cartridge.

Figure 9 is a cross-section behind the head of O.

Figure 11 is a perspective view of the extractor shown in

Figure 12, which is a partial section of a fire-arm differing from the preceding mainly in that the spiral spring is compressed by the backward instead of the forward action of the bolt.

Figures 14 and 15 represent, in sectional elevation, the compound bolt, as applied to a breech-loader, which may be made to act also as a repeater;

Figure 13 being a cross-section of the same.

Figure 16 is a sectional elevation of a form of fire-arm in which the hammer is placed in advance of the T-bolt.

Figure 17 gives a front view of a tool for forming the recess for the lip of the extractor, fig. 3.

Figure 18 is a longitudinal section of a pistol, with the above compound bolt, and

Figure 19, a horizontal section on the line 1-2 of the same.

In all the figures—

A represents the fore part of the plunger, a being used to specialize the rib on its upper part, which fills up the usual cartridge-slot in the breech-case.

A' denotes that part of the plunger behind the transverse or T-bolt.

a', the rib on same, which fills up the continuation of the cartridge-slot.

The plunger A A' is made to carry the transverse bolt T, figs. 1, 4, and 5, capable of sliding vertically in a mortise in the plunger, which also carries a pin or striker, C, here centrally disposed, but inclined, in the case of a rim-fire cartridge, as shown in fig. 1^a.

A hammer, actuated by a main-spring, and released by a trigger-sere, strikes the end of C, through a slot in the bottom of the rear part of the breech-case B¹.

Both hammer and trigger-sere are mounted in a slot in the lump K', on the trigger-plate K, being carried on plain taper pins, driven through the cheeks of K', and kept in place by a thin disk, k, impinging on their heads, fig. 4, which disk is fixed by a central screw, serving as a stop-pin for the hammer, when the trigger-plate is not in place.

The main-spring, one end of which may act as a sere-spring, or they may be separate springs, is fixed in a recess or dovetail in K, and secured by a pin driven through a loop on the guard F, which loop passes through both the main-spring and K.

The fore part of the guard is also fixed by a pin passing through a stud on the former.

The trigger-slot is continued to the stud-hole, through which the enlarged head of the trigger-sere may be passed, in order to get it into place.

This is done after the main-spring has been partially fixed in its recess.

A pin, V, screwed to the hand-part of K, serves as a button for the sling, which may be transferred to another button, V', and so drawn tight up to the stock.

The hammer strikes the pin C, and so explodes the cartridge. The recoil is taken by the plunger, which is locked by the bolt T, the stem of which passes through a hole in the lower part of the breech-case, here somewhat strengthened; while the cross-head rests in grooves on the upper part of same.

The stem of the T is slit, so as to pass over a reduced part of C, and thus retains it in place; and a small stop-piece, n, is fixed in the slit, so as to limit the upward motion of T by coming in contact with the pin C. The small projections n', fig. 6, and n'', fig. 12, serve the same end.

The lower part of the stem is rounded, so as to slide in the bottom of the breech-case, when $\mathbf{T}$ is raised and drawn back.

The latter brings with it the bolt A , drawing the spent cartridge by means of the extractor E , which has a considerable amount of traverse on a reduced part of the bolt A .

If E is formed, as in fig. 3, the rib a is undercut by an annular cutter, so as to make way for the ring on the end of E ; or the rib a may be left entire, and a corresponding space cut out of the ring, as shown in fig. 1^a.

A disk-headed plug, G , fig. 2, screwed into the head of A , serves as a stop and guide for the extractor, and also for the forward motion of the pin C , a reduced part of which strikes through its axis, fig. 1, or through the disk-margin, as in fig. 1^a.

The lip of the extractor e is of conico-ellipsoidal form, fitting into a corresponding recess in the rear of the cartridge-chamber, which does not impede the ramming of the cartridge. This recess may be conveniently formed by the tool, shown in fig. 17, consisting of a round plug, J , fitting into the breech-case B , and carrying on one side a long rod, with a conical cutter, y , on its fore end.

The recess is produced by rocking the plug J , after the revolving cutter y has entered a certain way, by means of a lever, standing out from the plug.

When A is drawn back, it brings the hammer to full cock, and rides over the face of the same.

A groove, g , in A , allows it to pass over the projecting end of the pin P , till it is stopped by the latter coming in contact with G , and with the extractor E , which then bears against G , fig. 4.

The fresh cartridge is dropped into the breech-case, through the slot, and pushed into the chamber by the forward motion of A . The $\mathbf{T}$ -bolt is then pushed down, as shown in fig. 1, and slightly held by the click-spring s^2 , fig. 5, or s^6 , fig. 14.

A recess, x , allows the striker C to advance so far as to explode the cartridge when the bolt is locked.

The bolt D , sliding in a dovetail in the tail-piece A' , and steadied by the spring s , gives further security, as it may be pushed in by the thumb, so as to intercept or block the face of the hammer when the latter is at full cock. It is drawn out before firing.

The bolt $\mathbf{T}$, though stronger when of rectangular section, may be round, as $\mathbf{T}^2$, fig. 12. It may be undivided if the hammer is mounted before it at $\mathbf{T}'$, fig. 16.

Instead of the stem of the bolt $\mathbf{T}$ sliding in a mortise in A , it may have a somewhat wider slot, and each leg be made to slide in grooves in opposite sides of A , as shown in fig. 6. The small projections n^1 act as stops, to limit the motions upwards.

The legs of $\mathbf{T}^1$ being elastic, can be sprung into place. With this construction of $\mathbf{T}^1$ the pin C^2 , fig. 10, is used with its rear end somewhat enlarged. It is introduced through a hole in A' , which is afterwards plugged up.

Figs. 18 and 19 show the compound bolt as applied to a pistol or small hand-rifle.

The trigger-plate K^2 has a lump at its fore end, which is screwed to the breech-case B^1 . A small gap is cut out of this lump to admit the fork f , which passes on each side of the hammer, and acts as a link to connect the trigger and the spring-detent s^1 , the action of which will be obvious.

The striker C being inclined, is put in from the rear end. The cartridge is extracted as in the form shown in fig. 16, about to be described, but the tilting-tooth is here on the trigger h . This and part of f work freely in the slit of the $\mathbf{T}$ -bolt. The small stops n^2 are screwed or otherwise fixed to $\mathbf{T}$, after the last is in its place in the plunger.

A small sliding safety-stud, d , is used to block the head of the detent s^7 . It is pushed forward by the thumb before firing.

P^2 is a pin, screwed into B^1 , the end of which enters a groove in the side of the plunger A' , and serves as a stop for the same when drawn back.

The above fire-arm may be modified to act as a repeater. To this end, a number of cartridges are introduced into a tube, Q , in any known way, and fed up, by the usual spiral spring, towards the carrier U^1 , by which each is brought up, in succession, opposite the barrel. The breech-case B^2 is extended downwards, and has a parallel slot or mortise, of a width to admit the body of the cartridge, and not the flange. Opposite Q this slot is bored out, so as to allow the flange to pass g^2 , till it meets the upright grooves g^1 , one in each cheek of B^2 , which should be of a width and depth just sufficient to allow of the flange rising freely in them when the cartridge is lifted by the carrier U^1 , which has fillets to slide in the said grooves.

The carrier consists of a hollow thimble, U , free to move vertically in a cylindrical enlargement of the above slot, g^3 , which is continued downwards in a lump on the trigger-guard, and of a bracket, U' , standing out from such thimble.

The carrier being in the position shown in fig. 14, receives a cartridge from Q . The bolt A is then unlocked, and drawn back in the usual way, extracting the spent cartridge by means of the fixed hook E^2 . A is stopped by the spring-detent S' , which supplies the place of the pin P in fig. 4. The carrier is at the same time released, and is forced up by a spiral spring into the thimble U , into the position shown in fig. 15, carrying with it the cartridge, which is caught between the bracket U' and the bridge B^3 , over the fore part of the slot.

The muzzle of the gun should be inclined upwards, in order that the spent cartridge, which is ejected by the ascent of the fresh one, may not catch on the bridge. A flap, u , on the fore part of U' , partially closes the cartridge-tube Q in the mean time. (See fig. 15.) The forward motion of A pushes the cartridge into the barrel, and U' is so constructed that the fixed hook E^2 can underrun the cartridge-flange. Two light springs, s^4 , are added, to support the rear end of the cartridge, but yield to the forward motion of A , which slightly depresses the carrier. The descent of the bolt $\mathbf{T}$ forces the carrier to its former position, where it is caught by the detent S' , and receives a fresh cartridge. A sliding stop, r , is used, which, when pressed up, cuts off the supply of cartridges, and the arm may then be used as an ordinary breech-loader, similar in action to that already described, the cartridge being inserted by hand, between the carrier U' and the bridge B^3 . The trigger-plate B^3 is a continuation of B^2 . It will be evident that a repeating-pistol can also be made on this plan.

In fig. 16, an arrangement is shown, differing from the first mainly in the disposal of the lock, which is placed before instead of behind the $\mathbf{T}$ -bolt. The last may, in this case, have a solid square or round stem, the ascent of which is guided and limited by a spring-click, s^5 .

The hammer, pivoted in the stud N , strikes a short percussion-pin, C^3 , of the ordinary character, through an opening in B and A . It is detained and released by a trigger-sere engaging with its head. The pin C^3 is supported at the back by a small bolt, t , transverse to A .

The cartridge is extracted by the spring-hook E^3 , and, when drawn clear of the barrel, may be tilted out by a small tooth, t , on the hammer, travelling in the groove g^4 , and catching the lower edge of the flange. A sliding crutch, D^2 , acted on by the spring s^3 , prevents the hammer striking home when in its normal position, (fig. 16,) by intercepting the ends of the swivel-pin, which project beyond the tumbler-arm. D^2 is manipulated by an outside stud, which is pressed back by the left hand while firing.

Figs. 8 and 9 show an arrangement in which the hammer and main-spring are replaced by a spiral spring and striker, O, sliding on a reduced part of C¹, and striking against a shoulder on same. The spring is compressed by a spring-detent, S, catching against a hook or toe on the striker O when A is pushed inwards. The detent-head also serves, instead of P, fig. 1, as a stop for A, and it may be undercut, so as to admit of being locked by sliding forward the forked safety-bar D¹. It is joined to the trigger by the stirrup m, and both are fixed in their places before the barrel and breech-case are put in the stock.

The bolt A is here shown as formed with a conical thimble, I, of spring-tempered steel, fitting closely a recess in the end of the barrel, and with a central column, H, to protect the fore end of C¹, and support the base of the cartridge, which should be of the nature of that used with the Chassepot rifle. The annular air-chamber tends to blow forward the remains of the cartridge. By reducing the pin C at its fore end, and giving it the full stroke, by bringing the shoulder further back, it may be made to fire the Prussian needle-cartridge.

A further modification, adapted for short-flanged cartridges, is shown in fig. 12, differing from the last, in that the spiral spring is compressed by the backward motion of A against a fixed plug, R, which forms a sort of false breech, and is united by side screws to the end of the breech-case, B⁴. The disk-headed striker O is detained and released by the sere S³, catching on its toe, which runs in a groove in the breech-case.

The sere may be blocked by turning the pin D³ through a quarter circle, by means of its outside thumb-piece.

The plunger is a short one, and the rib a' covers the spiral spring, and is free to slide back in the gap in the breech-case, as before. A square or round-stemmed T-bolt may be used.

The extractor E¹, figs. 11 and 12, is narrow, and formed of an upper and lower piece screwed together, so as to form lateral V's, embracing corresponding ridges in the sides of a slot in B⁴, in which it slides for a short distance. Opposite parts of E¹ are cut away, so as to leave only a narrow strip, over which the slit in the stem of T² may pass. A small tooth on the lower half of E¹ rises above the upper part of same, and is caught by the fore part of the plunger A, and so extracts the cartridge when the plunger is drawn back to compress the spring.

I do not claim a longitudinal plunger, or even a longitudinal plunger in combination with a transverse locking-bolt, both of which have been already used; but

What I claim as my invention, and desire to secure by Letters Patent, is—

The combination of a longitudinal plunger with a locking-bolt of T-form, which, when raised, acts as a handle for manipulating the said plunger, while performing its various functions of ramming and drawing the cartridge, (where the cartridge requires to be drawn,) and of cocking the lock, the whole constructed and operating substantially as herein set forth.

ANDREW WYLEY.
